MONEY BOX

August Wilhelm Wolters, Southampton, N. Y.

Application June 9, 1949, Serial No. 98,003

4 Claims. (Cl. 109—46)

1

The present invention relates to money safes and the like and refers more particularly to means for safekeeping of money so as to have it accessible to authorized persons and to cause it to fall to a stronger and more inaccessible container if an unauthorized person attempts to open the first mentioned safekeeping means.

The principal object of the present invention is to provide a more simple money box than those now available.

A subsidiary object is that the box shall be completely automatic in operation, in the sense of requiring a predetermined manner of operation for opening by an authorized person, and further that the box may be closed in the ordinary way and that such closing shall be effective to reset its internal mechanism so that unauthorized opening shall automatically cause the money to fall to the remote place of safekeeping.

In accomplishing the objects of the present invention a chute is provided having a rectangular lid pivotally connected to the rear wall thereof. Substantially perpendicularly extending from the inner surface of the lid is a metal eye. A heavy bar hangs therefrom by means of an interengaging eye, the bar extending straight down from the eye of the lid in all positions of the lid, also extending through a guide eye in all said positions, and in the closed position of the lid further engaging two eyes set one below the other and connected to the sliding bottom of the money compartment. The bottom is supported on rollers and is actuated by coil springs to a forward position in which it leaves the money compartment in communication with the chute. The bottom may be pushed rearwardly, compressing the springs, and may be held in such position by engagement of its eyes with either the bar, if the lid is closed, or with a detent which may be actuated from a hidden position, such actuation being necessary to authorized operation of the box so as to expose its contents for removal.

Other objects of this invention will in part be obvious and in part hereinafter be pointed out. The invention accordingly consists in the features of construction, combinations of elements and arrangements of parts which will be exemplified in the constructions hereinafter described. In the accompanying drawing, in which is shown one of the various possible illustrative embodiments of this invention:

Figure 1 is a fragmentary front elevation of the money box.

Figure 2 is a vertical section on the line 2—2 of Figure 1.

2

Figure 3 is a similar view showing the relation of parts after unauthorized use.

Figure 4 is a section on the line 4—4 of Figure 3. Referring now in detail to the drawings, my improved money box 10 comprises the side wall portions 11, 12, 13, 14 of which wall 12 may be called the rear wall, and wall 14 may be called the front wall, wall 14 further comprising the door 15 hinged to wall 11. A lid 16 is hinged to rear wall 12 and is swingable from the closed position of Figure 2 to the open position of Figure 3.

Four substantially vertical partitions 17, 18, 19, 20 extending laterally of box 10, that is, between walls 11 and 13, define the spaces 21, 22, 23 which together constitute the money compartment 24 of the box 10, it being understood that one or more such spaces 21, 22, 23 may be used as desired for the storing of paper money in vertical position. The partitions 25, together with front wall 14 and partition 17, serves to enclose a dead space 26.

Bottom portion 27 is slidably supported on rollers 28 and guided by guide strips 29, and movable from a closed position, Figure 2, in which it serves as the bottom of money compartment 24, to an open position, Figure 3, which leaves money compartment 24 in open communication with chute 30 leading vertically downward therefrom to a remote strong money container, such as a burglar proof safe, not illustrated.

Bottom portion 27 comprises a block 31 firmly connected to its under side, and two eyes 32, 33. Eye 32 extends rearwardly from bottom portion 27 and eye 33 extends rearwardly from block 31 and in vertical alinement with eye 32. Eyes 32, 33 together constitute the keeper means of the bottom locking means more fully described hereafter.

Bottom portion 27 is recessed as at 34 for the reception of compression coil springs 35 whose free ends bear against rear wall 12. Springs 35 thus tend to actuate portion 27 to the open position of Figure 3.

An eye 36 is fixed in lid portion 16 and engages an eye 37 which is integral with the rod 38, rod 38 constituting a detent means by which bottom portion 27 may be locked closed as illustrated in Fig. 2, in which rod 38 passes through the eyes 32, 33 when lid 16 is closed. Eye 39 fixed in rear wall 12 serves as a guide for rod 38. Eye 36 is so proportioned and situated relative to hinge 40 of lid 14 that rod 38 moves vertically upon the swinging of lid 16 around hinge 40, there being substantially no movement of rod 38 other than vertical.

55 A further detent means for locking bottom por-

tion 27 in closed position while lid 16 is open is the hook 41 pivotally mounted in rear wall 12 and having a handle portion 42 extending exteriorly thereof. Hook 41 has a weight 43 or other means tending to keep its hook portion depressed as illustrated in the full line position, and thus out of engagement with bottom portion 27.

In operation, it is obvious that money placed in money compartment 24 will fall into chute 30 if lid 16 is raised by an unauthorized person, for rod 38 will come free of both eyes 32, 33 and springs 35 will actuate bottom portion 27 into the dead space 26, depriving the money or other contents of spaces 21, 22, 23 of support so that it falls into chute 30.

The advantage of dead space 26 is seen in Figure 3, as successful operation of the device might be prevented if bottom portion 27, in order to completely withdraw from money compartment 24, had to protrude beyond an outer wall of box 10. A person standing in the path of bottom portion 27 would in such case obstruct its motion and prevent operation.

In order to prepare box 10 for use after unauthorized use, door 15 is opened and bottom portion 27 is pushed rearwardly to the position of Figure 2 and handle 42 is depressed, engaging hook 41 in eye 33. The box will now hold its contents even with lid 16 open.

To obtain access to money in box 10 the authorized person will press down on handle 42 while raising lid 16. Hook 41 thus enters eye 33, and as soon as rod 38 disengages eye 32 the forward pressure of springs 35 on bottom portion 27 will frictionally retain hook 41 in eye 33, thus keeping the bottom of money compartment 24 in closed position so that its contents are available from above.

No resetting of mechanism is necessary after authorized use of box 10, as the closing of lid 16 drops rod 38 to the bottom of eye 33, disengaging hook 41.

It will thus be seen that there is provided a device in which the several objects of this invention are achieved, and which is well adapted to meet the conditions of practical use. As various possible embodiments might be made of the above invention, and as various changes might be made in the embodiments above set forth, it is to be understood that all matter herein set forth or shown in the accompanying drawing is to be interpreted as illustrative and not in a limiting

What is claimed is:

1. In a money box, the combination with side wall portions and a lid portion constituting a box, said lid portion being pivotally connected to one of said side wall portions and swingable from an open to a closed position, said box comprising a money compartment open at the bottom, a bottom portion for said money compartment, said bottom portion being supported in operative relation to said money compartment so as to be slidable from a closed to an open position, of means actuating said bottom portion into a normally open position and lock means for holding said bottom portion in closed position, said lock means comprising keeper means comprised by said bottom portion, said lock means further comprising detent means pivotally connected to

and actuated by said lid portion and engaging said keeper means and maintaining said bottom portion in closed position when both said lid and said bottom portion are in closed position, said 10 lock means further comprising further keeper means, and further detent means engageable with said further keeper means when said bottom portion is in closed position and said lid portion is partially open to keep said bottom portion in closed position, said further detent means comprising means operative to keep said further detent means normally out of engagement with said further keeper means.

2. In a money box, the combination with side wall portions and a lid portion constituting a box, said lid portion being pivotally connected to one of said side wall portions and swingable from an open to a closed position, said box comprising a money compartment open at the bottom, a bottom portion for said money compartment, said bottom portion being supported in operative relation to said money compartment so as to be slidable from a closed to an open position, of means actuating said bottom portion into a normally open position and lock means for holding said bottom portion in closed position, said lock means comprising keeper means on said bottom portion, said lock means further comprising detent means in the form of a rod pivotally suspended from said lid and extending into said keeper means when both said lid and said bottom portion are in closed position, said rod being gradually withdrawn from said keeper means by opening of said lid so as to come entirely free of 30 said keeper means before said lid is fully open, said lock means further comprising separate detent means, said separate detent means being normally out of engagement with said keeper means and being optionally engageable in said keeper means when said rod is partially withdrawn and said bottom portion is still in closed position, said rod, in case said separate detent means is so engaged, further directly contacting and physically displacing said separate detent means from said keeper means in the closed position of said lid and of said bottom portion.

3. In a money box according to claim 2, said keeper means comprising a plurality of eyes in spaced relation and in substantially vertical alignment, said rod engaging all of said eyes when said lid and said bottom portion are in closed position, said separate detent means being engageable with the lowermost of said eyes upon the withdrawal of said rod therefrom by raising 55 of said lid.

4. In a money box according to claim 2, said side wall portions further enclosing a dead space into which said bottom portion is actuated in the open position of said bottom portion.

AUGUST WILHELM WOLTERS.
